CLAIM

The ornamental design for a furniture part, as shown and described.

DESCRIPTION

FIG. 1 is a top, front and right side, perspective view of a furniture part in a retracted position according to my new design.

FIG. 2 is a top plan view thereof.

FIG. 3 is a left side elevational view thereof, the opposite right side elevational view being a mirror image.

FIG. 4 is a rear elevational view thereof, the opposite front elevational view being a mirror image.

FIG. 5 is a bottom plan view thereof.

FIG. 6 is a top, front and right side, perspective view thereof in an extended position at a reduced scale; and,

(Continued)

FIG. 7 is an exploded, top, front and right side, perspective view thereof.

The broken lines in FIG. 6 are for environmental purposes only and form no part of the claimed design.

1 Claim, 4 Drawing Sheets
